UNITED STATES PATENT OFFICE.

MILEDEN S. MONDAY, OF CANEY, OKLAHOMA

METAL RAILWAY-TIE.

1,266,139.

Specification of Letters Patent. Patented May 14, 1918.

Application filed January 4, 1918. Serial No. 210,315.

To all whom it may concern:

Be it known that I, MILEDEN S. MONDAY, a citizen of the United States, residing at Caney, in the county of Atoka and State of Oklahoma, have invented certain new and useful Improvements in Metal Railway-Ties, of which the following is a specification.

This invention relates to railway ties, and 10 it relates especially to an improved form of metal tie.

One of the objects of this invention is to provide a metal tie that is comparatively light and inexpensive, while being strong, 15 rigid, durable and perfectly efficient.

Another object is to provide a tie of this character that may be formed either by pressing it from blanks of sheet metal or by casting it integrally.

20 Another object is to provide means to render impossible the spreading of rails secured on ties of this character.

Another object is to absorb the shock or jar caused by the travel of rolling stock 25 along the rails that are supported by my improved ties; and—

Another object is to combine means for retaining the shock absorbers in place and for staying the sides of the tie so as to prevent collapsing of the tie when it is subjected to an exceedingly heavy load or severe shock.

Other objects and advantages may become apparent to persons who read the following 35 details of description in connection with the accompanying drawings in which,—

Figure 1 is a top plan view of the tie with fragments of two rails secured thereon:

Fig. 2 is a sectional view taken along the 40 line 2—2 of Fig. 1:

Fig. 3 is an end view of the tie with a fragment of a rail secured thereon; and—

Fig. 4 is a perspective view of portions 45 of the tie.

Referring to these drawings in detail, in which similar reference characters correspond to similar parts throughout the several views:—

The main body 10 of the tie is preferably 50 in the form of a channel beam, or U-shaped in cross section, the height and width being approximately equal. The horizontal lower side 11 of the tie joins the vertical sides 12 at right angles, and wide horizontal 55 flanges 13 are formed on the upper edges of the sides 12 and extend in opposite direc-

tions therefrom. Each end portion of each flange 13 is provided with a depression or rail seat 14 and with shoulders 15 at opposite sides of each rail seat. 60

Combined partitions and braces or struts 16 have apertured flanges 17 extending laterally from the intermediate portion thereof, and two of these members 16 are secured adjacent to each end of the body 10. Bolts 65 18 extend through the apertures of the flanges 17 and through corresponding apertures 19 of the body 10, for securing the members 16 in spaced relation within the body 10, so as to form a housing for a cushioning member or shock absorber 20. The member 20 is preferably of wood for the sake of minimizing in the cost of production, and also for the sake of resiliency. This member is cubical and is, therefore, easily 75 and economically obtained by sawing a rectangular beam of wood into proper lengths. The grain of the wood may be either horizontally or vertically disposed, and the blocks may be a little higher than the depth 80 of the body 10 at the seats 14 so that the rail may primarily and normally rest on the block independently of the seats 14; but when an exceptionally heavy load is placed on the rails, the seats 14 supplement the 85 blocks 20 in supporting the rails and their load. Each housing formed by the elements 12 and 16 effectually confines its block 20 in registry with the rail seats 14, while the shoulders 15 prevent lateral movement or "spreading" of the rails at their bases. 90

In order that the rails may be securely retained between the shoulders 15, I provide combined abutments and keepers 21, 95 each of which is formed integrally and comprises a flange 22 and a rail-engaging element 23, the latter comprising a surface 24 which engages the base-flange of the rail, also a surface 25, which engages or abuts 100 against the web of the rail. The members 21 are each secured to one of the flanges 13 by means of a bolt 26 that extends through an aperture of this member and through an aperture 27 in the flange 13. 105

Each tie comprises eight of the members 21, four at each end portion; and for securing a rail to one end of the tie, two complementary pairs of these members are employed. 110

In securing a rail to one of these ties, the base flange of the rail is placed on the block

20 and is thereby held slightly spaced above the seats 14, while the edges of the base flanges are between and against (or only slightly spaced from) the shoulders 15; the members 21 are then placed in the respective position shown in Fig. 1; and the bolts 26 are then placed, and the nuts thereof are tightened until the members 21 are tightly secured on the flanges 13. In thus tightening the bolts 26, the outer edges of the flanges 13 are drawn upward, their inner edges being held rigid by the block 20, so that these outer edges may touch or nearly touch the base of the rail. Now when an exceedingly heavy weight on the rail compresses the block 20, it also depresses the outer edges of the flanges 13, so that the latter coöperate with the block 20 in providing a cushion seat for the rail. It will be seen that the inherent spring action of the flanges 13 coöperates with the members 21 for continually holding the rail on the block 20, so that "hammering" of the blocks by the rails is effectually obviated, and no rattling or jarring will occur as when ties of ordinary construction are used.

Each member 21 is provided with a shoulder 28 which coöperates with the shoulders 15 for preventing lateral movement of the contiguous base flange. Each flange 22 lies flat against the contiguous vertical portion 12, and prevents turning of the member 21 around its bolt 26, and coöperates with the

members 16 for holding the block 20 in proper relation to the tie and rail.

What I claim as my invention is:

1. A metal tie, comprising a channel beam having opposed outwardly extending flanges disposed to form rail seats, and a rail securing member bolted to each flange at the ends of the rail seat thereof, said member comprising a depending portion to engage the inner face of a side wall of the channel beam, and an inner element to extend over the base flange of the rail and engage the web thereof.

2. A metal tie, comprising a channel beam having opposed outwardly extending flanges disposed to form rail seats, a resilient block within the channel beam to support the rail, braces secured to opposite vertical walls of the channel beam and in contact with opposite sides of the block, and a rail securing member bolted to each flange at the ends of the rail seat thereof and comprising a depending portion to engage the inner face of a side wall of the channel beam and a side of the block, and an inner element to extend over the base flange of the rail and engage the web thereof.

In testimony whereof I affix my signature in presence of two witnesses.

MILEDEN S. MONDAY.
